UNITED STATES PATENT OFFICE.

FRANK W. SEVERIN, OF CHICAGO, ILLINOIS.

FUEL-FEED MECHANISM FOR OIL ENGINES.

Application filed July 27, 1925. Serial No. 46,379.

The invention relates to fuel feed mechanism for oil engines.

One object of the invention is to provide improved fuel feed mechanism which is controlled by a governor which regulates the volume of fuel injected into the engine responsive to power requirements of the load, and in which the volume of the charges of the fuel is controlled by variation of the stroke of the fuel pump. Another object of the invention is to provide improved mechanism of this type in which the point of commencement of fuel injection is always the same under different speed and load conditions, the variation of the pump stroke resulting in varying the end of the injection periods only.

A further object of the invention is to provide improved means for controlling the fuel pumps to selectively render any one or all of them inoperative or for manually operating the pumps when desired.

Other objects of the invention will appear from the detailed description.

The invention consists in the several novel features hereinafter set forth and more particularly defined by claims at the conclusion hereof.

In the drawings: Fig. 1 is a longitudinal section of mechanism embodying the invention. Fig. 2 is a section on line 2—2 of Fig. 1. Fig. 3 is a section taken on line 3—3 of Fig. 1. Fig. 4 is a horizontal section taken on line 4—4 of Fig. 1. Fig. 5 is a detail sectional view of one of the roller carrying slides and its guide. Fig. 6 is a section on an enlarged scale of one of the fuel pumps. Fig. 7 is a detail of the pump plunger. Fig. 8 is a detail of the adjustable collar on the pump plunger. Figs. 9 and 10 are details of the pump operated valve in the pump barrel.

The invention is exemplified in mechanism supported in a suitable frame or bracket 10 which is usually mounted on the engine casing and carries a hollow shaft 11 which is geared to and driven by the crank shaft of the engine at a rotative speed suitable to the cycle of the engine. The mechanism shown is for a two-cylinder engine comprising a fuel pump and connections for each engine cylinder, although it is to be understood that the invention may be applied to an engine having one or more cylinders, as well understood in the art.

Each pump comprises a barrel or casing 12, which is provided with lugs 12^a, which are bolted to the outer sides of the upright members 10^a of the frame 10, and a piston 14, which is slidable in and fitted to a cylinder 13 in said casing. A spring 15 is applied to impart the retractile stroke to the pump piston, its outer end being interposed between the inner end of the casing and a collar 16 fixed to the piston. Collar 16 is 60 adjustably connected to said piston, so that its outer end, which acts to feed the fuel oil to the injector, may be adjusted to vary the effective cycle of each pump stroke. For this purpose, collar 16 is connected by a 70 screw-thread 16^a to a screw-threaded stem 14^a on the pump piston, and is split so that it may be firmly held in its assigned position by clamp-screws 16^b. A fuel chamber 21 is integrally formed with the pump casing to dispense with the necessity of providing communications between them. A delivery pipe 22 is connected to deliver fuel from a suitable source of supply into a duct 22^a, which delivers the fuel oil to the bottom of chamber 21. A pet-cock 22^b is connected to chamber 21, so that in initially filling it, air can be discharged from the chamber until it has been partially filled. A drain cock 22^c is also connected to said chamber. The outer portion of the pump piston 14 is hollow, as at 14^b, and radial recesses 14^c are cut in the periphery of the pump piston to deliver fuel oil from the duct 22^a into the hollow portion or outer 80 end of the piston. The outer end of the piston is formed with a conical seat 14^d to engage the conical end of a valve 19, which is slidable in the outer end of pump cylinder 13. This valve is provided with a series 85 of longitudinally extending peripheral slots 19^a which permit oil to flow from the pump cylinder into a chamber 18 adjacent the outer end of the cylinder and with an annular shoulder 19^b adapted to engage a shoulder 12^b formed in the casing 12, to limit the inward movement of valve 19 by a spring 20, which acts to hold the valve in its normal position and permits it to be shifted outwardly by and with the pump piston during the injection cycle of the pumping stroke. The inner end of the spring is confined in a cylindrical chamber in the valve, and its outer end is held in a plug 18^a which is screw-threaded to the cas- 90 95 100 105 110

ing 12 and closes the outer end of chamber 18. From chamber 18, the oil is forced through a duct 18^b into a pipe 26, which is connected to deliver the oil in regulated 5 quantities to the inspirator or injector for the engine cylinder. A check-valve 27 prevents backflow of the fuel.

In operation, the stroke of piston 14 is greater than that required for the maximum 10 charges of fuel required by the engine, and each pumping stroke includes an idle cycle until the outer end 14^d of the piston seats against the valve 19, during which period oil will flow from the opening 14^b in the piston 15 through cylinder 13 and slots 19^a into the chamber 18, and a cycle during which the piston is effective to pump oil while its seat 14^d engages the inner end of valve 19 to 20 cut off communication between the oil in the piston and the chamber 18, and forces the valve outwardly to force a charge of oil from the chamber 18 to the injector. By 25 varying the stroke of the pump piston to increase or diminish the active cycle of its stroke, the volume of the charges may be 30 regulated responsive to the power requirements of the load under control of the governor which correspondingly varies the stroke of the pump piston. This construction exemplifies one in which regulation of the volume of the charges of fuel injected is 35 regulated by the pump piston and dispenses with the necessity of a suction, by-pass or metering valve. The upper portion of chamber 21 forms an air cushion to destroy the inertia of the line of oil between the supply tank and the oil in the piston and cylinder.

The mechanism for operating the pumps from shaft 11 comprises a cam 30 which is 40 journaled on an eccentric 31 which is keyed to the drive-shaft 11. This cam is adapted to operate the pumps in rotative succession, to vary the stroke of the pump pistons 45 responsively to load variations by an automatic or centrifugal governor. Each pump piston is operated by cam 30 through a roller 32 which bears against the periphery of said cam and is journaled on a pin 33. Said pin and roller are carried in a cylindrical 50 member 34 which is slidably mounted in a depending lug 35 of an annular frame member 36, which is secured to the top of frame 10 by bolts 37. Each lug 35 is provided with inwardly extending arms 38 between which 55 the inner end of member 34 is guided. A plate 39, secured to a flattened portion on the underside of member 34, engages the underside of arms 38 to secure the member and roller carried thereby against rotation. An 60 abutment plate 40 held in the inner end of member 34 on shoulder 41 in said member is adapted to engage the inner end of the collar 16 to impart the pumping stroke to the pump piston. Spring 45, acting against 65 collar 16, retains the roller 32 in engage-

ment with the periphery of cam 30, thus reTRACTING the roller with the pump piston. The active cycle of the pump pistons, which forces oil to the injectors, occurs while the rollers 32 are in engagement with a portion 70 30^a of the cam which is concentric with the eccentric 31, and as a result the active cycle of the pump piston always commences at the same point relatively to the crank shaft and piston movements of the engine, and this, 75 in practice, has been found to be an important feature, because it insures the timely delivery of the charges into the combustion chambers under varying speeds and loads. This result is attained, because rotative adjustment of the portion 30^a of cam 30 by the governor does not vary the points at which the pump pistons engage the valves 19 and commence the active pumping cycles. Normally, the cam portion 30^a of cam 30 is 80 adapted to impart the maximum pumping stroke to the pistons, and as it is rotated by the governor, the points at which the pumping operation commences will remain the same, but the length of said strokes will be reduced to correspondingly reduce the active pumping cycles of the pistons and the extent to which the valves 19 are shifted, so 85 that the charges of oil pumped to the injectors will be decreased responsively to the 90 governor movement. This construction exemplifies one in which variable pumping strokes are imparted to the pump pistons to correspondingly vary the charges delivered 95 to the injectors, without varying the time of commencement of the delivery of the charges. It also exemplifies a construction in which the variations in the fuel charges delivered to the injector are effected by variation of the piston stroke and the valve 100 operated by the piston, so that separate operating mechanism for a suction or control valve is dispensed with.

The governor mechanism for rotatably adjusting the cam 30 around eccentric 31 comprises a pair of weights 43, each pivoted by a pin 44 to an arm or extension 45 which is integral with the eccentric 31, so that the governor arms will rotate with the shaft 11. Each weight is provided with an integral inwardly extending arm 46 provided with gear-teeth 47 which mesh with a gear 48 integrally formed on the lower end of cam 30. A spring 50 is applied to each of the governor weights 43 to yieldingly resist their outward movement by centrifugal force and to retract them. Each spring is connected to an arm 51, which is pivoted by pin 52 to one of the eccentric arms 45. The tension of these springs is variable to adapt the 110 governor for different running conditions, and for this purpose each arm 51 is provided with an integral abutment lug 53 adapted to be engaged by a pin 54 which is radially 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940

eccentric 31. These pins may be adjusted radially to rock arms 51 to vary the tension on springs 50 by a plunger 55, which is slideable in the hollow shaft 11, and has a tapered 5 lower end which, by vertical movement, is adapted to shift the pins 54. The upper end of plunger 55 is fixedly secured to a nut 57 which is screw-threaded to the inner periphery of the hub 58 which is rotatable 10 and confined against longitudinal movement in a head 59 which is secured by bolts 60 to the annular frame member 36. A cap 60' is rotatably held on the upper end of said hub and carries pins 61 which extend through 15 holes in nut 57, so that by rotation of the cap, nut 57 may be turned to longitudinally adjust the plunger 55. A spring-pressed finger lever 62 is pivoted, at 63, to said cap and provided with a tooth 64 adapted to enter 20 notches 65 in hub 58 to secure the nut in its adjusted position. Cap 60' is removably held on hub 58 by a screw 66 which extends into an annular groove 67 in the upper portion of hub 58. An adjustable stop pin 68 25 is carried by one of the arms 45 on eccentric 31 to fix the normal position of said cam, and an adjustable stop-pin 69, carried by one of said arms 45, is adapted to engage the arm 46 of one of the governor arms to fix the 30 maximum movement of cam 30 by the governor.

In practice, it is sometimes desirable, for example in starting, to manually operate one or more of the pumps. It sometimes occurs 35 that it is desirable to render one of the pump pistons inoperative by the cam 30, for example, if one of the engine cylinders is not firing properly. For this purpose, mechanism is provided by which the pump pistons 40 may be manually operated or selectively rendered inoperative. This mechanism comprises an arm 70 for each pump piston, which is pivoted at 71 to the underside of head 59 and is adapted to engage the head 45 33^a of a roller pin 33 to force one of the pump pistons outwardly against the force of its retracting spring 15, so that its operating roller 32 will be held free from engagement with the cam 30. Each arm 70 50 also carries an upwardly extending stud 72, which is adapted to be operated to shift the arm by a cam 73. This cam is disposed adjacent the underside of head 59, and comprises an annular rib 74 having an eccentric slot or cut-away portion 75 therein. Said cam is integral with the hub 58, which extends through head 59, and a lever 76 for operating the cam is fixed to said hub. A 55 spring 77 is applied to each of the arms 70 to cause its stud 72 to be normally held against the inner periphery of rib 74. Each of these springs has one of its ends connected to a stud 78 fixed to head 59 and its other end connected to an arm 79 integrally 60 formed with arm 70, and these connections

are arranged so that the spring will cross the dead-center and exert an inward pull on arms 70 when the studs 72 have been shifted to engage the outer periphery of rib 74. Normally, the arms 70 and cam 73 will be in 70 the position shown by full lines in Fig. 2, in which the studs 72 will engage the inner periphery of rib 74 to hold the arms 70 in their inoperative position, so that the heads 33^a of the roller pins 33 will be free to permit the rollers and pump pistons to be operated by the cam 30. When it is desired to manually operate the pumps, as in starting the engine, the operator will rotate the lever 76, so that, as the cam 73 is operated, springs 80 77, acting on arms 70, will swing them outwardly to cause studs 72 to enter the groove 75. After entering said groove, one side 75^b thereof will act as a cam to force the studs 72 outwardly so that arms 70 will engage 85 heads 33^a and impart a pumping stroke to the pistons. The operator may rotate the cam to operate one of the arms 70 or to operate them successively. This manual pumping operation is effected by rotating 90 the cam 73 in one direction. By reversing the rotation of said cam, the side 75^b of groove 75 will engage the studs 72 and force them inwardly to engage the inner periphery of rib 74, which will force the arms 70 95 into the position shown by full lines in Fig. 2. By imparting selective strokes to the cam 73, either of the arms 70 may be operated to impart pumping strokes to its pump piston or both of the arms may be operated 100 in rotative succession. The cam may also be manipulated to selectively hold either or both of the arms 70 and the pump pistons controlled thereby in position to render the pistons inoperative by cam 30. It will be understood that springs 77 are applied to normally hold studs 72 in a medial position between the inner and outer peripheries of rib 74, so that the studs will be positively 105 operated to swing the arms inwardly or outwardly according to the direction in which the cam 73 is rotated. A pin 80, carried by lever 76, is adapted to enter sockets 81 in the upper face of head 59. These are located at points at which it may be desired 110 to lock the cam 73, to hold said cam in such positions. Pin 80 is releasable by a finger-piece 82, which has a stem which is slidably mounted in the handle 76^a of lever 76, and is suitably connected to release pin 80 against 115 the force of a spring 83 which is applied to normally hold said pin in its operative position.

This construction exemplifies controlling 120 mechanism for fuel pumps, by which they may be singly, selectively or collectively rendered inoperative, and by which they may be singly or collectively operated to manually operate the fuel pumps.

Mechanism for controlling the starting 130

of the engine by compressed air is mounted in the lower portion of the frame 10, but since this does not form any part of the present invention, it is not described.

6. The invention is not to be understood as restricted to the details set forth, since these may be modified within the scope of the appended claims, without departing from the spirit and scope of the invention.

10. Having thus described the invention, what I claim as new and desire to secure by Letters Patent, is:

1. In fuel feed mechanism for oil engines, the combination of a reciprocatory pump 15 for feeding fuel oil to the engine cylinder comprising a piston and a cylinder, a cam for operating the piston to pump the oil, a valve in the cylinder, for rendering the piston effective to deliver oil and operated by the piston, and means for adjusting the cam to vary the pumping stroke of the piston to vary the charges delivered to the engine.

2. In fuel feed mechanism for oil engines, 25 the combination of a reciprocatory pump for feeding fuel oil to the engine cylinder comprising a piston and a cylinder, a rotatable cam for operating the piston to pump the oil, a valve in the cylinder, for rendering the piston effective to deliver oil, and operated by the piston, and mechanism for adjusting the cam to vary the active cycle of the pumping stroke of the piston and to correspondingly vary the operation of the 30 valve to vary the charges delivered to the engine.

3. In fuel feed mechanism for oil engines, 40 the combination of a reciprocatory pump for feeding oil to the engine cylinder, comprising a piston having a duct extending to its inner end, and a cylinder in which the piston is slidable, means for delivering oil into the hollow piston, a cam for operating the piston, a valve in the cylinder for closing the duct to render the piston effective to deliver oil, operated by the inner end of the piston, and having a duct through which oil will flow, except when the valve is operated by the piston, and means for adjusting the 45 cam to vary the pump strokes.

4. In fuel feed mechanism for oil engines, 55 the combination of a supporting frame, an engine-driven shaft mounted in the frame, a reciprocatory pump for delivering charges of oil to the engine, comprising a piston and a cylinder supported by the frame and extending laterally from the shaft, a valve in the cylinder operated by the piston and for rendering the latter effective to deliver oil, 60 a cam driven by the shaft for imparting pump strokes to the piston, and means for adjusting the cam to vary the pumping stroke of the piston so as to vary the charges delivered to the engine.

5. In fuel feed mechanism for oil engines,

the combination of a supporting frame, a vertically extending engine-driven shaft mounted in said frame, a reciprocatory pump for delivering charges of oil to the engine comprising a piston and a cylinder supported by the frame and extending laterally from the shaft, a valve in the cylinder operated by the piston and for rendering the latter effective to deliver oil, an eccentric on and rotatable with said shaft, a cam for imparting pump strokes to the piston, mounted to rotate relatively to and driven with said eccentric, and a governor connected to rotate the cam on the eccentric so as to vary the piston stroke. 70

6. In fuel feed mechanism for oil engines, the combination of a reciprocatory pump for delivering charges of oil to the engine, comprising a piston and a cylinder, an engine driven shaft, an eccentric on and rotating 85 with said shaft, a cam for imparting pumping strokes to the piston mounted to rotate relatively to and driven with said eccentric, and a governor connected to rotate the cam on the eccentric to vary the piston stroke, 90 and a valve operated by and coacting with the piston to vary its effective pumping cycle and the volume of the charges delivered responsively to variations in its stroke. 95

7. In fuel feed mechanism for oil engines, the combination of a reciprocatory pump for delivering charges of oil to the engine comprising a piston and a cylinder, an engine driven shaft, mechanism for imparting variable strokes to the piston mounted to rotate relatively to and driven by said shaft, a governor operatively connected to said mechanism, and means operated by and coacting with the piston to vary the effective cycle of its stroke and the volume of the charges delivered responsively to variations in its stroke, said means being formed so that the delivery of the oil by the pump will begin without substantial variation in the timing of the commencement of the oil delivery by the pump while said mechanism is in different positions. 100

8. In fuel feed mechanism for oil engines, the combination of a reciprocatory pump for delivering charges of oil to the engine comprising a piston and a cylinder, an engine driven shaft, an eccentric on said shaft, a cam for imparting pumping strokes to the piston mounted to rotate relatively to and driven with said eccentric, a governor connected to rotate the cam relatively to the eccentric to vary the piston stroke, and means coacting with the piston to vary its effective pumping cycle and the volume of the charges delivered responsively to variations in its stroke, said cam being rotatable to vary the effective cycle of the pumping stroke without substantial change in the timing of the commencement of the oil delivery by the pump. 115

9. In fuel feed mechanism for oil engines, the combination of a reciprocatory pump for delivering charges of oil to the engine comprising a piston and a cylinder, an engine driven shaft, an eccentric on and rotating with said shaft, a cam for imparting pumping strokes to the piston mounted to rotate relatively to and driven with said eccentric, a governor connected to rotate the cam relatively to the eccentric to vary the piston stroke, and means coacting with the piston to vary its effective pumping cycle and the volume of the charges delivered responsively to variations in its stroke, said cam being rotatable by the governor without substantially varying the timing of the commencement of the oil delivery by the pump while the cam is in its different positions.

10. In fuel feed mechanism for oil engines, the combination of a reciprocatory pump for delivering charges of oil to the engine, comprising a piston and a cylinder, an engine driven shaft, an eccentric on and rotating with said shaft, a cam for imparting pumping strokes to the piston mounted to rotate relatively to and driven with said eccentric, a governor connected to rotate the cam relatively to the eccentric to vary the piston stroke, and a valve operated by the piston coacting with it to vary its active cycle and the volume of the charges delivered from the cylinder by the pump responsively to variations in its stroke, said cam being rotatable to its different position without changing the timing of the commencement of the delivery of oil by the piston.

11. In fuel feed mechanism for oil engines, the combination of a plurality of pumps for feeding oil to the engine, each comprising a piston and a cylinder, engine-driven means for operating the pistons to pump fuel, a governor for adjusting the cam to vary the pumping strokes of the piston, and a manually shiftable cam provided with means to selectively render any or all of the pistons inoperative.

12. In fuel feed mechanism for oil engines, the combination of a plurality of pumps for feeding oil to the engine, each comprising a piston and a cylinder, an engine-driven cam for operating the pistons to pump fuel, a governor for adjusting the cam to vary the pumping strokes of the pistons, and a manually shiftable cam provided with means to render any of the pistons inopera-

tive and for manually operating any or all the pistons to pump oil.

13. In fuel feed mechanism for oil engines, the combination of a drive-shaft, a plurality of pumps for feeding oil to the engine, each comprising a piston and a cylinder, a cam on said shaft for operating the pistons to pump fuel, a governor for adjusting the cam to vary the pumping strokes of the pistons, and a manually shiftable cam mounted to rotate around said shaft and provided with means to render any of the pistons inoperative and to manually operate them to pump fuel.

14. In fuel feed mechanism for oil engines, the combination of a pump for feeding oil to the engine comprising a casing having a cylinder therein and a slidable piston in said cylinder, mechanism for operating the pump piston to deliver fuel to the engine, a valve in said casing and operated by the piston, a connection for delivering oil into the top of said casing, a chamber formed in an integral portion of the casing below the piston and said connection and communicating with said delivery means forming an air cushion to destroy the inertia of the line of oil, and a cock on said receptacle for exhausting the air therefrom.

15. In fuel feed mechanism for oil engines, the combination of a plurality of pumps for feeding oil to the engine, each comprising a piston and a cylinder, engine-driven means for operating the pistons to pump fuel comprising a cam, a governor for adjusting the cam to vary the pumping strokes of the piston, and means whereby any of the pump pistons may be selectively rendered inoperative by the cam and whereby the pistons may be manually operated.

16. In fuel feed mechanism for oil engines, the combination of a plurality of pumps for feeding oil to the engine, each comprising a piston and a cylinder, engine-driven means for operating the pistons to pump fuel comprising a cam, a governor for adjusting the cam to vary the pumping strokes of the piston, and a rotatable member whereby any of the pump pistons may be selectively rendered inoperative by the cam and whereby the pistons may be manually operated.

Signed at Chicago, Illinois, this 9th day of July, 1925.

FRANK W. SEVERIN.
